UNITED STATES PATENT OFFICE

155,058

DESIGN FOR A BOX OR THE LIKE

Alexander C. H. Weiss, Chicago, Ill.

Application August 13, 1946, Serial No. 132,496

Term of patent 7 years

(Cl. D58—13)

To all whom it may concern:

Be it known that I, Alexander C. H. Weiss, a citizen of the United States, residing at Chicago, in the county of Cook and State of Illinois, have invented a new, original, and ornamental Design for a Box or the like, of which the following is a specification, reference being had to the accompanying drawing, forming part thereof.

Figure 1 is a perspective view of a box or the like, in closed position, embodying my new design; and

Figure 2 is a perspective view of the box or the like in open position showing the pin cushion in the cover and the compartmented base.

I claim:

The ornamental design for a box or the like, as shown and described.

ALEXANDER C. H. WEISS.
